PILL DISPENSER WITH INDICATING MEANS

BACKGROUND OF THE INVENTION

This invention relates to a pill dispenser and in particular to a pill dispenser having means for automatically indicating the removal of each pill from the dispenser.

In writing out prescriptions it is generally the practice of physicians to state that a pill should be taken at prescribed intervals. The intervals may be only a matter of hours, or, on the other hand, may be on the basis of one per day, or perhaps one every other day. In any event, it is essential that the user be able to determine whether or not he has taken a pill for that interval since it is quite possible that his memory will fail him. Various devices have been contrived in which the user, upon taking a pill from the dispenser or container, will, in a separate physical action, record this fact. For those persons who are always able to remember to make a recording mark or other similar act, such a procedure is sufficient. However, many a person has tended to forget entering on his own personal record the fact that he has taken a pill for a specified day. Thus, he is confronted with the problem of trying to remember whether or not he actually took a pill for that interval.

Various dispensers have been designed with automatic indicating means coordinated with specially arranged pills. For example, pills have been spring loaded in tubes or disposed in a unique pattern to provide accurate coordination with an adequate indicating means. In such dispensers of the prior art it has been necessary to develop suitable equipment for efficiently and quickly loading the dispenser with pills. In addition, such equipment has had to provide means for assuring sanitation of the pills during loading of the dispenser. Furthermore, the dispenser necessarily had to be designed to easily receive the pills; and, consequently, the pills in some instances were not fully sealed from the atmosphere. Thus, the pills could be affected by moisture in the atmosphere as well as being subjected to possible contamination.

SUMMARY OF THE INVENTION

The dispenser of this invention has been designed to receive conventionally packaged pills which are individually wrapped and therefore well protected from contamination. In particular, these pills are packaged in blister packages having a foil backing or other easily tearable material and a covering formed from thin plastic material with individual recesses for the pills. Thus, no investment in new equipment is necessary to load the dispenser of this invention inasmuch as the conventional blister package of pills is simply inserted into the dispenser. The indicating means of our dispenser comprises an elongated device bearing a plurality of indicia which may be the days of the week or smaller increments such as divisions of the days into hourly periods. This indicating means is snapped into a suitable compartment in the pill dispenser which is designed to maintain the indicating means and its indicia in registered alignment with the pills in the blister package. The retaining means in the dispenser compartment permits manual rotation of the indicating means in order to initially align the appropriate indicia with the first pill to be taken on a designated day or hour. No additional setting of the indicating means is needed until a new supply of pills is placed in the dispenser.

Thus, it is one object of this invention to provide a new and improved pill dispenser utilizing a conventional blister package of the pills. Another object of this invention is to provide a low-cost dispenser which may be used indefinitely for periodical refills. A further object of this invention is to provide a dispenser having an indicating means to enable the patient to readily determine whether or not he has taken a pill for the prescribed interval. Other objects and advantages of this invention will be made apparent upon reading the following disclosure in conjunction with the drawing.

BRIEF DESCRIPTION OF THE DRAWING

FIG. 1 is a perspective view of the pill dispenser of this invention partially exploded to more clearly disclose the indicating means.

FIG. 2 is a view in cross section taken along line 2-2 of FIG.

1.

FIG. 3 is a bottom plan view of the dispenser.

FIG. 4 is a view in cross section taken along line 4-4 of FIG.

10 3.

DESCRIPTION OF THE PREFERRED EMBODIMENT

Referring to FIG. 1, the dispenser of this invention is shown having a base 11 with an integrally connected cover 13. However, it is to be understood that the invention herein is not necessarily dependent on having a cover. In this illustrated embodiment base 11 and cover 13 may be formed of a suitable plastic material such as polypropylene in accordance with conventional injection molding techniques. Thus, cover 13 is hinged to base 11 by a thin web of plastic material 14 which is frequently referred to in the molding trade as a "living hinge." Cover 13 may be provided with a latch element 16 which cooperates with element 17 on the base to selectively maintain the dispenser in a closed position. Both the base and cover have been tapered in order to accommodate indicating means 19. As shown in FIG. 1, the indicating means in this embodiment comprises a hollow elongated multifaced member. This indicating means may be formed from plastic material by standard extrusion techniques. Inasmuch as the illustrated dispenser has been designed for assisting the patient to take one pill each day, indicating means 19 has been provided with seven surfaces 21 extending along its full length. In addition, each surface 21 has been marked off into seven equal segments 22, thereby permitting each surface 21 to carry the indicia 24, which in this instance are the seven days of the week. It is to be noted that each longitudinal row of indicia 24 arranges the days of the week in chronological order. The first 40 day for each of these chronologically arranged indicia is different from the first day for the other longitudinally arranged indicia. This arrangement is such that the indicia as arranged in their peripheral pattern also appear in a chronological order. The seven surfaces 21 are defined by recessed lines 25 in order to permit the patient to easily rotate the indicating means once it is positioned in the dispenser.

Base 11 is formed with an indicating means compartment 27 which is open on its underneath side. The top portion of the compartment is defined by an arcuate surface 29 having a 50 reference means in the form of a longitudinal slot 30 and a stepped-down opening 32. A retaining hub 34 may be integrally molded within compartment 27 at one end. As shown in FIG. 2, retaining hub 34 has a pawl 35 with a top surface 37 and an inclined surface 38. This retaining hub is formed to 55 permit a small amount of deflection along its arm 40.

At the opposite end from retaining hub 34 a retaining clip 42 is molded within compartment 27. This clip comprises a thin strip of plastic material which will readily deflect and yet 60 maintain resiliency to provide a biasing effect on indicating means 19.

A plurality of pills 45 are individually wrapped in transparent blisters 46 formed from a plastic material. As shown in FIG. 4, the blisters have a paper or foil backing 48 which is 65 easily ruptured.

In some instance it is essential that the patient take a certain type of pill for a given number of days which is then followed by a different type of pill. In this sequential type of dosage it is 70 therefore essential that the blister package containing pills 45 is inserted into the dispenser in its proper position to provide the correct consumption of pills. Thus, the blister package is formed in this embodiment with a V-shaped cutout 50 to coincide with a corresponding V-shaped projection 51 formed in the interior of base 11. The blister package may then be 75 inserted in the proper position and retained in base 11 by two or

more lugs 53. Indicating means 19 is inserted into compartment 27 by first placing the right end 55 of the indicating means onto retaining clip 42. This is accomplished by angling the indicating means into compartment 27 from its underneath side. After end 55 is butted against the inner surface of the compartment's end 56, the left end of the indicating means may be snapped over the retaining hub 34.

The indicating means is maintained in the dispenser in a snug fashion to avoid accidental rotation. Thus, as shown in FIG. 4, retaining clip 42 asserts a biasing effect on the inner surface of the indicating means to force it against the inner surface of end 56. The left end of the indicating means rests on the top surface 37 of the retaining hub's pawl 35 (FIG. 4).

The patient will normally receive the dispenser with the indicating means positioned in compartment 27. If the blister package containing the pills is not already inserted in base 11 the patient snaps the package therein with cutout 50 aligning with projection 51. In accordance with the prescription given the patient, he then selects the designated day of the week for taking the first pill and aligns that day with the longitudinal slot 30 at the left end of compartment 27. Rotation of the indicating means 19 may be accomplished by grasping it between the thumb and forefinger at the stepped-down portion 32 and on the underneath side. It is to be noted that slot 30 is of a predetermined width to permit the registering and viewing of only one series of seven days from the top side of compartment 27. Thus, the patient is now ready to remove the first pill. This is accomplished by pushing the pill in the upper left-hand corner of the blister package through its corresponding opening 58 in base 11. The backing 48 on the blister package is thereby ruptured and the pill will fall into the hand of the patient holding the dispenser. In a like manner the second through seventh pills of the top row of the blister

package are taken at their designated intervals. Since in this embodiment the indicia bear the seven days of the week with one pill taken each day, it is apparent that the same indicia registered with slot 30 are correct for the second and third rows of pills in the blister package. Upon taking the 21st pill, the blister package may be removed from base 11 and a new package inserted with proper rotation of the indicia with respect to the prescribed time for taking the first pill.

Although only one embodiment of this invention has been described and illustrated, it will be apparent to those with skill in the art that modifications can be made without departing from the spirit of this invention or the scope of the appended claims.

We claim:

- 15 1. A pill dispenser with indicating means comprising: a pill receiving base member, said base member supporting an indicating means housing containing an elongated indicating means with a plurality of surfaces extending along its length, each of said surfaces bearing a plurality of sequential indicia, said indicating means being hollow with open ends, a pair of retaining elements integrally formed in said indicating means housing extending into said open ends rotatably supporting said indicating means, a reference means comprising a slot in said indicating means housing in registry with said indicia in one of said surfaces of said indicating means, and a plurality of pills arranged in at least two straight rows on said base member parallel to said slot and aligned with each other and said indicia in registry with said slot.
- 20 2. A dispenser as defined in claim 1 in which one of said retaining elements is a thin strip of plastic material biased against the inner surface of said hollow indicating means.
